UNITED STATES PATENT OFFICE.

CHARLES S. F. KIRKEBY, OF LONG ISLAND CITY, ASSIGNOR OF ONE-THIRD
TO LOUIS W. UNHOLTZ, OF NEW YORK, N. Y.

CABINET-CHAIR.

SPECIFICATION forming part of Letters Patent No. 358,616, dated March 1, 1887.

Application filed November 8, 1886. Serial No. 218,229. (No model.)

To all whom it may concern:

Be it known that I, CHARLES S. F. KIRKEBY, of Long Island City, in the county of Queens and State of New York, have invented certain new and useful Improvements in Cabinet-Chairs, of which the following is a specification.

This invention has reference to an improved cabinet-chair which combines the advantages of a comfortable arm-chair with those of an invalid-chair, so as to be specially useful in sick-rooms; and the invention consists of a chair the back and seat portions of which are rigidly connected at the meeting edges and pivoted to the rear part of the chair-frame, so as to be capable of being tilted in backward direction until stopped by side recesses of the back. The supporting-frame is provided below the seat with an opening and a sliding drawer containing a flat pan or urinal, which is ready for use when the combined seat and back is tilted and the seat placed in an upright position. When the seat is returned to its normal position on the supporting-frame, it is retained thereon by suitable locking devices, which are released when the combined back and seat are to be tilted.

In the accompanying drawings, Figure 1 represents a side elevation of my improved cabinet-chair. Fig. 2 is a vertical transverse section of the same on line $\alpha\alpha$, Fig. 1; and Fig. 3 is a vertical longitudinal section of the chair, showing the combined back and seat tilted back, so as to permit the use of the chair as a cabinet.

Similar letters of reference indicate corresponding parts.

In the drawings, A represents the supporting-frame of my improved cabinet-chair, which frame is preferably provided with arms A'. The seat B and back C are rigidly united at their meeting edges, so as to form one combined body, which is pivoted to lugs $\alpha\alpha$ of the supporting-frame A, so as to be tilted from the normal position (shown in Fig. 1) into a backwardly-thrown position, (shown in Fig. 3,) in which position the seat assumes nearly an upright position, so that it can be used as a back for the party sitting on the supporting-

frame A. The back C has side recesses, a' , 50 at the lower part, which fit around the lugs $\alpha\alpha$ and serve as stops for the combined back and seat when they are tilted in a backward direction.

The supporting-frame A is provided with an 55 opening, b, below the seat B, and below said opening with a flat pan or urinal, D, which is located in a drawer, D', that can be drawn out at the rear part of the frame A, for the purpose of removing the urinal. Spring-catches or 60 other locking devices, d, are applied to the seat B or back C, and serve to engage recesses of the supporting-frame A or arms A', so as to lock the back and seat to the supporting-frame A when the former are in a normal position 65 in the frame A, as shown in Fig. 1.

Any other suitable locking device may be used, as I do not confine myself to the special kind shown.

My improved cabinet-chair has the advantage of being used as a comfortable arm-chair for the sitting-room, and also as an invalid-chair in bed-rooms. When used as the latter, a suitable disinfectant is stored away in the sliding drawer D' to remove any obnoxious 75 smells. The chair can be adjusted for use with great facility, and is specially adapted for hospitals and sick-rooms generally.

Having thus described my invention, I claim as new and desire to secure by Letters Patent— 80

1. The combination of a supporting-frame having an opening below the seat, a pan or urinal below said opening, and a combined seat and back, which are rigidly united at their meeting edges and pivoted to the rear part of the supporting-frame, substantially as set forth.

2. The combination of a supporting-frame provided with an opening below the seat, a sliding drawer having a pan or urinal below 90 said opening, a combined seat and back, which are united rigidly at their meeting edges and pivoted to the rear part of the supporting-frame, and a locking device by which the combined seat and back can be locked to or released from the supporting-frame, substantially as set forth.

3. The combination of a supporting-frame

provided with an opening below the seat and fixed rear lugs, a pan or urinal below said opening, and a combined seat and back, which are rigidly united at their meeting edges, said back being pivoted to said lugs and provided with side recesses acting as stops, substantially as set forth.

In testimony that I claim the foregoing as my invention I have signed my name in presence of two subscribing witnesses.

CHARLES S. F. KIRKEBY.
